FOREIGN PATENT DOCUMENTS

JP D1130144 * 12/2001

Primary Examiner — Shannon W Morgan*Assistant Examiner* — Altaira J Swangin(74) *Attorney, Agent, or Firm* — AEON Law, PLLC;
Adam L.K. Philipp; Jonathan E. Olson(57) **CLAIM**

The ornamental design for a footcare appliance, as shown and described.

DESCRIPTION

FIG. 1 is a top right perspective view of a footcare appliance;

FIG. 2 is a front side view thereof;

FIG. 3 is a right side end view;

FIG. 4 is a top plan view thereof; and,

FIG. 5 is a bottom plan view thereof.

The broken lines of FIGS. 1-5 illustrate portions of the footcare appliance that form no part of the claimed design. The broken lines of FIG. 1 depict an elongate aperture portion on one end that forms no part of the claimed design.

1 Claim, 2 Drawing Sheets(56)
